McKibbin

UNITED STATES PATENT OFFICE.

JOSIAH H. L. TUCK, OF SAN FRANCISCO, CALIFORNIA.

HEAT-TRANSMITTER.

SPECIFICATION forming part of Letters Patent No. 323,545, dated August 4, 1885.

Application filed May 14, 1884. (No model.)

To all whom it may concern:

Be it known that I, JOSIAH H. L. TUCK, a citizen of the United States, residing at San Francisco, in the county of San Francisco and State of California, have invented certain new and useful Improvements in Heat-Transmitters for Treating Unwieldy Articles or Objects, such as boilers, &c.; and I do hereby declare the following to be a full, clear, and exact description of the invention, such as will enable others skilled in the art to which it appertains to make and use the same.

My invention relates to a device for applying heat to large masses or surfaces of iron or other metal, where it would be inconvenient or impossible to subject the said mass or surface to the fire in the ordinary manner.

As heretofore pursued among boiler-makers and other workers in heavy iron, the method of keeping the iron in a condition for bending, welding, or otherwise working it has been to subject the mass or surface to the fire, in the ordinary manner of such work, as often as it becomes cold. This has to be repeated many times on various kinds of work, and at each repetition great labor, trouble, and delay are entailed.

By means of my invention I am enabled to apply heat and flame at any point upon a mass or surface of metal without moving or disturbing the same and from a fire at a distant point, so that from the ordinary forge, hearth, or furnace used for heating the mass or surface when placed upon or in said forge, hearth, or furnace I obtain the heat and flame to apply to the metal at a distant point without any handling or labor of any consequence, and without the trouble of building a fire upon, in, under, or about the mass or surface to be treated. For this purpose I construct and employ a hood or receptacle to place over the fire to receive the heat, flame, and burning gases. This receptacle or hood is formed of any fire-proof material and of any appropriate or desired form—square, cylindrical, oblong, polygonal, or otherwise, as may be desired—with a convergent top or dome, to the apex of which is secured a flexible, fire-proof tube or conveyer to lead the products of combustion off to be delivered at the desired point upon the mass or surface of metal. This pipe may be formed of short iron or other metallic

sections having knuckle joints to insure pliability and capacity for bending in any direction; or it may be made of asbestos or other naturally flexible fire-proof material. At the end where it is joined to the apex of the hood or receptacle a swivel joint is provided, so that the pipe can readily be turned round at this point and extended in any direction without twisting the pipe. At the delivery end the pipe is provided with a distributor to scatter and disseminate the heat and flame over and upon the mass or surface under treatment in such a manner as to produce the best results with the least expenditure of fuel or heating-power. I also provide means for regulating the extent and number of the escape-openings for the flame and heat in this distributor, so that I can make the same distributor serve to deliver the same amount of heat and flame over a large surface, and gently or very forcibly through a small number of openings over or upon a contracted point.

The details of my invention, as practically applied for heating purposes on large unwieldy objects, will be more fully and clearly understood from the following description by figures and letters.

In the accompanying drawings, I have shown what I consider a preferable means for carrying the invention into practice. It will be remembered, however, that I do not confine myself to any particular form of hood or receptacle, or material of which it is formed, nor the character of nor material for forming the pipe nor the size or style or the distributor on the deliver end thereof.

In the said drawings, Figure 1 is a general side elevation of the device, showing a portion of boiler-plate and a portion of the furnace. Fig. 2 is a central vertical section of the hood, showing the non-conducting covering for the hood. Fig. 3 is a face view of the distributor. Fig. 4 is a cross-section of the same on an enlarged scale.

Similar letters of reference indicate corresponding parts in all the figures where they occur.

Let Z represent a part of a steam-boiler, hull of a metallic vessel, or other large mass or surface of metal, and Y the hearth, forge, furnace, or other fire-place where the fire is made. Over this fire I place my hood or receptacle A.

As shown in the drawings, this is cylindrical in form over most of its body; but, as already explained, it may be of any form. The top or dome A' of the hood is conical or funnel-shaped, as shown, to draw the heat and flames into the pipe B, which is to convey them off to the point of application.

The receptacle A, dome A', and pipe B may either or all be covered with some approved 10 non-conducting material, such as is in general use for boiler and steam-pipe covers. This covering is shown at a a' b in Fig. 2.

The pipe B is secured upon the apex of the dome A' by means of joint, as shown at B', 15 which allows the pipe to be turned in any desired direction without twisting the pipe.

The pipe is made of any fire-proof material, as metal or asbestos. When made of metal, it must be provided with flexible joints, such as 20 knuckle-joints, as shown in Fig. 2. It may be coated both inside and outside with any approved material capable of withstanding the heat, so as to prevent the escape of heat; or the coating may be dispensed with on either 25 the inside or outside, or both.

The pipe B may be of any desired length and at the delivery end is provided with a distributor, C, which is shown in the form of an elongated rose or box punctured on its 30 face so as to thoroughly scatter and disseminate the heat and flame.

In the distributor under the face I provide a slide, C', which works in ways in the side of the distributor, as shown at C', Fig. 4, and 35 springs C³ are provided to hold the slide securely in any position in which it is placed. By means of this slide I am enabled to expose the entire lot of apertures in the face of the distributor to the passage of heat and flame, or 40 may slide it into the distributor and hide more or less of the apertures so as to condense and intensify the flow of heat and flame. When the slide is drawn out to the full extent, as shown in Figs. 1 and 3, the whole face of the 45 distributor with its punctures is exposed to the passage of the heat and flame and the flow is gentle. When the slide is pushed in so as to allow only a few apertures to be open to the passage of heat and flame, the flow will be 50 forcible and intense and will heat up a point or small surface in a very short time.

If desired, the distributor may be of any other form, or a simple nozzle may be substituted for it.

55 As thus constructed and applied, my device will be found to possess qualities of a most desirable character, and will work with great economy of time, labor, and fuel in heating or keeping hot, masses, surfaces, &c., where 60 it is not feasible or convenient to apply heat in any of the ordinary methods.

In using my device the first heat may be taken in the ordinary way, and then the subsequent heats made by use of my apparatus, or the metal kept continuously hot by the use 65 thereof.

The force of the furnace-blast will concentrate the flame in the hood, dome, and pipe and produce a most intense volume of flame and heat to pass out through the pipe which 70 may be applied at any point within reach of the pipe.

As shown in the drawings, and as hitherto described, my invention has been mentioned only in connection with heating metal for 75 purposes of working it; but in the application of my device it will not be limited to such use alone, as it will be found to be eminently useful in melting or refining ores or metals, and in many other situations where it is desirable to apply heat at a distance from the 80 fire or source of heat.

Having thus described my invention, what I desire to claim and secure by Letters Patent is—

85 1. The herein described apparatus for applying flame and heat, consisting of the collecting receptacle adapted to receive and collect the heat and flame, and a fire-proof conveying-pipe of flexible character, and a suitable nozzle or distributor, as set forth.

2. The combination of the collecting receptacle A, having the conical or convergent top or dome adapted to receive and collect the heat and flame, and a fire-proof conveying-pipe secured to the apex thereof, said pipe 95 being flexible, substantially as set forth.

3. The apparatus described for collecting and conveying heat, flame, and other products of combustion, consisting of the receptacle A, having the convergent top A', for location over the furnace or fire, the pipe B, united to the apex of the top A', by a swivel-joint, said pipe being formed of such material or in such a manner as to be flexible and 100 fire-proof, and a distributor, C, attached to the outer end of the pipe, as set forth.

4. In a device for transmitting and applying heat, the combination, with the collector A, pipe B, and distributor C, of the slide C', 110 working under the punctured face of the distributor, substantially as and for the purpose set forth.

In testimony whereof I affix my signature in presence of two witnesses.

JOSIAH H. L. TUCK.
